CAP DIE

Carl W. Goodwin, Plainfield, N. J., and Kenneth R. Allen, Ridgewood, N. Y., assignors to American Seal-Kap Corporation of Delaware, Wilmington, Del., a corporation of Delaware

Application October 29, 1946, Serial No. 706,318

12 Claims. (Cl. 93—1.3)

1

This invention relates to dies for making paper bottle caps of the type having a central depressed diaphragm to seat on the internal ledge of a milk bottle or the like and a peripheral U-shaped housing to cover the pouring rim of the bottle.

An object of the invention is to provide a die of the above type having novel and improved details of construction and features of operation.

A more specific object is to provide a die of the above type in which air pressure is used for imparting the final forming pressure to the cap.

Another object is to provide a die of the above type which is adapted to operate in the commercial production of caps for long periods of time without repairs or adjustments.

Various other objects and advantages will be apparent as the nature of the invention is more fully disclosed.

Although the novel features which are believed to be characteristic of this invention are pointed out more particularly in the claims appended hereto, the nature of the invention will be better understood by referring to the following description taken in connection with the accompanying drawings in which a specific embodiment thereof has been set forth for purposes of illustration.

In the drawings:

Fig. 1 is a side elevation of the upper die showing the supporting ram in section;

Fig. 2 is a side elevation of the lower die showing the supporting base plate in section;

Fig. 3 is a longitudinal section through the upper die on an enlarged scale taken on the line 3—3 of Fig. 5;

Fig. 4 is a longitudinal section through the lower die on an enlarged scale taken on the line 4—4 of Fig. 6;

Fig. 5 is a transverse section through the upper die taken on the line 5—5 of Fig. 3;

Fig. 6 is a transverse section through the lower die taken on the line 6—6 of Fig. 4;

Fig. 7 is a broken perspective view illustrating a cap of the type which is formed by the dies of the present invention; and

Figs. 8, 9, 10 and 11 are partial vertical sections through the cooperating portions of the upper and lower dies showing successive stages in the cap-forming operation.

The die in accordance with the present invention is adapted to form a paper cap of the type shown in Fig. 7 which comprises a central depressed diaphragm 10 which is adapted to seat on the internal ledge of a milk bottle or the like, and pouring lip housing 12 which is adapted to

extend over the pouring lip of the bottle. The housing 12 comprises an inner vertical wall 13, a top wall 14, and an outer skirt 15. The top wall 14 is provided with raised beads or corrugations 16 which extend radially thereacross. A cap of this general type is disclosed more in detail in Martin Patent No. 2,221,197 dated November 12, 1940.

Referring to Figs. 1 and 2 an upper die 20 is shown as secured by suitable means in a ram 21 which forms a part of the forming press and is adapted to be reciprocated vertically.

A lower die 30 is held in a sleeve 31 which is secured in a base plate 32 forming a part of the base of the press. The lower die 30 is provided with a cap 33 which is adjustably secured to a base 32 which constitutes the bed of the press, by means of a bolt 34, bracket 35 and bolts 36 which are threaded into the base 32. The bolt 34 is provided with a spherical pressure surface 37 which equalizes the thrust upon the bolts 36.

The upper die 20, as shown in Figs. 3 and 5, comprises a shell 40 having a cap 41 which is secured thereto and is properly aligned by pins 42 having surfaces 43 which enter bores 44 in the shell 40. The shell 40 and shell cap 41 form a cylinder 45 to which air under pressure is supplied through a port 46.

The shell 40 carries a cylinder liner 47 (Figs. 3 to 11) in which a piston 48 slides. The piston 48 is preferably provided with oil grooves 49 and is sealed at the top by a cup packing 50 of suitable packing material such as rubber or leather and a compressible packing disc 51 preferably of rubber which is secured and clamped by a cover plate 52 and a center screw 53. Lubrication is provided by wicking 54 which extends downwardly from the packing 50 and communicates with an oil groove 55.

The lower end of the piston 48 is sealed by suitable packing material 58 which is compressed in a packing gland by a cap 59 and a clamping bolt 60.

An upper diaphragm body cap 65 is slidably mounted in the liner 47 below the piston 48 and is pressure sealed to the cylinder liner by means of a cup-packing 66 held against the upper diaphragm body cap 65 by means of a pressure plate 67 and a central screw 68. The plate 67 rests against an annular flange 69 formed on the lower piston cap 59.

The diaphragm body cap 65 is pinned to a diaphragm body 70 by means of pins 71. The diaphragm body 70 carries a diaphragm head 72 having a plurality of radially projecting fins 73

provided with bottom surfaces 74 which are adapted to register with the corrugations 16 on the top of the pouring lip housing 12 of the cap, and with an annular flange 75 having a lower surface 76 which forms the outer peripheral portion of the cap diaphragm 10. The head 72 is secured to body 70 by any suitable means such as pins 72a (Fig. 3).

A diaphragm plunger 80, having a lower surface 81 adapted to form the central portion of the cap diaphragm, is provided with a sleeve 82 which slides in a suitable chamber 84 in the diaphragm body 70 and carries a cap 83 which bears against a shoulder 85 of the body 70 to limit the downward movement of the diaphragm plunger 80. A spring 86 is seated within the chamber 84 of the diaphragm body 70 and bears against the cap 83 to press the diaphragm plunger 80 downwardly. An ejector pin 88 is slidably mounted in a bore in the diaphragm plunger 80 and is spring-pressed downwardly by means of a spring 89 which is seated against a shoulder 90 of the ejector pin and against the cap 83.

An upper corrugation ring 95 is positioned around the diaphragm body 70 and is secured to the shell 40 by means of set screws 96. The corrugation ring 95 is provided with a plurality of vertical slots 101 which register with and are adapted to receive the fins 73 of the diaphragm head 72. A key 97 attached to the top of the corrugation ring 95 by a screw 98 rides in a slot 99 in the diaphragm body 70 for aligning the slots 101 with the fins 73. The lower surface 102 of the corrugation ring is adapted to engage and form the top surface 14 of the pouring lip housing of the cap between the corrugations 16. A ring of soft material such as felt 104 surrounds the diaphragm body 70 and engages the corrugation ring 95 to clean the surface thereof and prevent any oil from dripping downwardly onto the cap being die-formed.

A skiving ring 110, having a surface 111 to form the outer skirt 15 of the cap, is held in a creasing ring 112 by means of a retaining ring 113 which is locked by a set screw 118.

The creasing ring 112 is provided with a fluted lower surface 114 which is adapted to crease the outer portion of the cap blank to facilitate the folding thereof downwardly to form the skirt 15. The creasing ring 112 is mounted on pins 115 which are positioned in the recesses 44 of the shell 40 and are held downwardly by springs 116 which are seated between the top of the pins 115 and the pins 42 above mentioned. The pins 115 are provided with shoulders 117 which limit the downward movement of the creasing ring 112. Studs 120, secured from the bottom of the shell 40, bear against the top of the creasing ring 112 for limiting the upward movement thereof and exerting the creasing and skiving pressures.

The port 46 is connected by means of a supply pipe 121 to a suitable source of fluid under pressure such as a compressed air tank not shown.

Referring to Figs. 4 and 6, the lower die comprises a shell 130 having a cylinder in which a cup 131 is slidably mounted. The shell 130 carries a lower cap 132 which is secured thereto by screws 133 and is provided with an annular flange 134 which extends within the cup 131. A head 135 is likewise mounted within the cup 131 and is provided with a top flange 136 between which and the flange 134 suitable compressible packing material 137a is positioned. The head 135 is secured by a nut 136 which bears against the end of a sleeve 137 forming a part of the cap 132 and serves to

compress the packing material 137a so as to provide a fluid seal against the inner surface of the cup 131. The head 135 is provided with an air passage 140 which communicates with a pipe 141 which may be connected to a suitable source of compressed air such as for example the same source as the pipe 121 leading to the upper die. The air passage 140 communicates with the interior 142 of the cup 131 and supplies the necessary pressure for holding the cup 131 in its upper position against a shoulder 143 formed in the shell 130.

The shell 130 carries a skirt sizing ring 150 having a top surface 151 which is adapted to size and shape the bottom of the cap skirt 15. The sizing ring 150 is clamped to the shell 130 by means of a retaining ring 152 and screws 153.

A draw ring sleeve 160 is mounted to slide within the sizing ring 150 and at its lower end rests upon the upper surface of the cup 131. A key 161, secured by a screw 153, enters a recess 162 in the draw ring sleeve for holding the latter in proper alignment and for limiting the movement of the sleeve when the cup 131 is removed for the purpose of assembly. A draw ring 164 slides within the sleeve 160 and is provided with a top surface 165 which is adapted to enter and shape the lower surface of the top 14 of the pouring lip housing 12 of the cap.

The draw ring 164 is provided with a lower flared surface 166 which engages a corresponding surface 167 of the draw ring sleeve 160 for limiting the downward movement of the draw ring 164. The draw ring 164 is pressed upwardly by a plurality of pins 168 mounted in recesses formed partly in the draw ring sleeve 160 and partly in a diaphragm draw block 170 which is mounted to slide within the draw ring 164. Springs 169 in said recesses bear against the pins 168 for urging the same upwardly. A stud 171, carried by the draw ring 164 slides in a recess 172 in the draw ring sleeve 160 for limiting the upward movement of the draw ring 164.

The diaphragm draw block 170 is provided with an upper surface 175 which is adapted to form the under surface of the cap diaphragm 10 and is held upwardly by means of a spring 176 which is seated within a recess 177 of said draw block and seats on a cap 178 which rests upon the top surface of the cup 131. The cap 178 is secured to the draw ring sleeve 160 by means of a retaining ring 179.

A lower creasing ring 180, having a fluted upper surface 181 adapted to crease the outer portion of the blank, is mounted on pins 182 having heads 183 which slide in recesses 184 in the shell 130 and are held upwardly by springs 185. The heads 183 limit the upward movement of the creasing ring 180.

It is to be noted that the area of the top of the cup 131 which is exposed to the air pressure within the cylinder 142 is greater than the area of the top of the piston 48 which is exposed to the air pressure within the cylinder 45. Hence more force is required to depress the cup 131 against this air pressure than is required to raise the piston 48.

The successive steps in the formation of a cap will be better understood by referring to the successive positions shown in Figs. 3 and 4 and in Figs. 8, 9, 10 and 11, respectively. Figs. 3 and 4 show the normal positions of the various die parts before the start of the forming operation. It will be understood that the cap blank in the form of a flat disc is placed across the top of the lower

die shown in Fig. 4 and rests upon the diaphragm draw block 170, the draw ring 164 and the creasing ring 180.

As the ram 21 of Fig. 1 brings the upper die downwardly against the cap blank, the ejector pin 88 is first retracted into the upper diaphragm plunger 80. The upper diaphragm plunger 80 is then retracted into the diaphragm head 72 against the force of the spring 91. The air pressure in the cylinder 45 is sufficient to hold the piston 48 in its downward position throughout this stage of the operation. The diaphragm plunger 80 and diaphragm head flange 75 are then forced downwardly within the draw ring 164 depressing the diaphragm draw block 170 against the force of the spring 176. The upper creasing ring 112 also strikes the blank against the lower creasing ring 180 to crease the outer marginal portion of the blank. The dies are then in the position shown in Fig. 8.

Continued downward movement of the ram causes the fins 73 of the diaphragm head 72 to push the paper of the cap downwardly against the lower draw ring 164 and thereby retract the lower draw ring 164 against the draw ring sleeve 160. The draw block 170 seats upon the cap 178 and the pressure on the diaphragm plunger 80 and diaphragm head 72 has caused the piston 48 to start retracting against the air pressure in the cylinder 45 as shown in Fig. 9.

Continued downward movement of the ram from the position of Fig. 9 causes the piston 48 to be further retracted against the air pressure within the cylinder 45 until the fins 73 of the diaphragm head 72 enter the slots 101 of the corrugation ring 95 and engage against the body of the corrugation ring. At the same time the studs 120 of the shell 40 engage the top of the creasing ring 112 and force the creasing ring 112 and skiving ring 150 downwardly to fold and skive the outer portion of the cap skirt 15 as shown in Fig. 10. The parts of the upper die are now locked by the corrugation ring 95 against further movement relative to the shell 40 and continued downward movement of the ram and shell serves to depress the draw ring sleeve 160 and the draw block 170 against the force of the air pressure within the cylinder 142 as indicated in Fig. 11 until the skirt of the cup 131 hits and becomes rigid with the cap 132 of the lower die. Inasmuch as the skiving ring 150 is carried rigidly by the shell 130 the skiving ring is not depressed and accordingly serves to compact and form the bottom of the cap skirt 15 and to press the cap material upwardly into the spaces in the slots 101 of the corrugation ring 95 below the fins 73, for compacting and forming the corrugations 16 of the cap. This constitutes the final forming operation.

When the ram is retracted the die parts return in the reverse order. The upward movement of the draw ring 164 with respect to the draw ring sleeve 160 serves to strip the cap skirt from the draw ring sleeve and allows the same to be readily removed from the lower die. The successive actions of the diaphragm plunger 80 and of the ejector pins 88 serve to strip the cap from the upper die and allow the same to rest between the two dies from which position it is removed by a dial plate not shown.

The use of air pressure in the cylinders 45 and 142 permits high operating pressures to be built up without acquiring the use of large springs which, in addition to complicating the apparatus, tend to break after a limited amount of use.

At the same time the differential pressure exerted on the piston 48 and the cup 131 due to the differences in size between the effective surfaces thereof provides for the proper operating sequence of the parts.

Although a specific embodiment of the invention has been shown it is to be understood that the invention is capable of various uses and that changes and adaptations may be made therein as will be readily apparent to a person skilled in the art. The invention is only to be restricted in accordance with the following claims.

What is claimed is:

- 15 1. A die for forming paper caps or the like having a central depressed diaphragm portion and a peripheral inverted container rim housing, said die comprising upper and lower die members mounted for relative forming and return movements and including upper and lower diaphragm forming members, conforming to the depressed cap diaphragm, a lower draw ring conforming to the inside surface of the peripheral rim housing and an upper pressure ring conforming to the top wall of said rim housing, said upper and lower die members each having a shell forming a compressed air cylinder, pistons in said cylinders to move vertically against the air pressure therein, means mounting said upper diaphragm forming member to move with said upper piston, means mounting said upper pressure ring to move with said upper die shell, means mounting said lower diaphragm forming member and said lower draw ring to move with said lower die piston at least in the final forming stage, said upper piston having an effective area less than that of said lower piston whereby the upper diaphragm forming member first cups the blank to form the depressed cap diaphragm and is then retracted against the air pressure in the upper shell cylinder while the upper shell feeds the upper pressure ring against the cap blank, and the lower diaphragm forming member and lower draw ring are then retracted against the air pressure in the lower shell cylinder by the pressure of the upper pressure ring in the final forming stage.
- 20 2. A die as set forth in claim 1 in which said lower piston comprises an inverted cup having a depending skirt sliding in said lower shell cylinder and a fixed head attached to said shell closes the lower end of said cylinder, said head having an air duct to supply compressed air to said cylinder.
- 25 3. A die as set forth in claim 1 in which said lower piston comprises an inverted cup having a depending skirt sliding in said lower shell cylinder and a fixed head attached to said shell closes the lower end of said cylinder, said head having an air duct to supply compressed air to said cylinder.
- 30 4. A die as set forth in claim 1 in which said lower diaphragm forming member is spring mounted on said lower piston to be retracted in response to pressure exerted by said upper diaphragm forming member for cupping and drawing the cap diaphragm prior to retraction of said lower piston against the air pressure in the lower shell cylinder due to the pressure applied to the blank by said upper pressure ring.
- 35 5. A die as set forth in claim 1 in which said upper diaphragm forming member comprises a head rigidly mounted with said upper piston to
- 40
- 45
- 50
- 55
- 60
- 65
- 70
- 75

form the inner vertical wall and at least a portion of the top wall of the rim housing of the cap, and a central diaphragm plunger slidably mounted in said head and spring pressed downwardly to engage the cap blank and to be retracted into said head prior to the cupping operation.

6. A die as set forth in claim 1 in which the upper piston carries packing to form a pressure seal with said upper cylinder and said upper diaphragm forming member is provided with a head slidable in said upper cylinder and engaging the lower end of said upper piston to be actuated therewith.

7. A die as set forth in claim 1 in which the upper piston carries packing to form a pressure seal with said upper cylinder and said upper diaphragm forming member is provided with a head slidable in said upper cylinder and engaging the lower end of said upper piston to be actuated therewith, said head also having packing means forming a pressure seal with said upper cylinder.

8. A die for forming paper caps or the like having a central depressed diaphragm portion and a peripheral inverted U-shaped container rim housing having an inner vertical wall, a top wall and an outer depending skirt, said die comprising upper and lower die members mounted for relative forming and return movements and including upper and lower diaphragm forming members conforming to the depressed cap diaphragm, a lower draw ring conforming to the inside surface of the peripheral rim housing, an upper pressure ring conforming to the top wall of said rim housing, an upper skiving ring conforming to the outer surface of the cap skirt for skiving and forming the same, a lower sizing ring adapted to extend between said skiving ring and said draw ring to exert die-forming pressure on the lower edge of the cap skirt, said upper and lower die members each having a shell forming a compressed air cylinder, pistons in said cylinders to move vertically against the air pressure therein, means mounting said upper diaphragm forming member to move with said upper die piston, means mounting said upper pressure ring and said skiving ring to move with said upper die shell at least in the final forming stage, spring means mounting said lower diaphragm forming member to move with said lower die piston at least in the final forming stage, means mounting said lower draw ring on said lower piston, and means mounting said sizing ring on said lower die shell, said upper piston having an effective area less than that of

said lower piston whereby the upper diaphragm forming member first cups the blank to form the depressed cap diaphragm and is then retracted against the air pressure in the upper shell cylinder while the upper shell actuates the upper pressure ring and the skiving ring, and the lower diaphragm forming member is depressed against its spring mounting to cup the blank prior to retraction of the lower draw ring against the air pressure in the lower shell cylinder in the final skirt sizing stage.

9. A die as set forth in claim 8 in which said lower piston comprises an inverted cup having a depending skirt sliding in said lower shell cylinder and a fixed head attached to said shell closes the lower end of said cylinder, said head having an air duct to supply compressed air to said cylinder and packing means carried by said head to seal against the inner wall of said depending piston skirt.

10. A die as set forth in claim 8 in which said upper diaphragm forming member comprises a head rigidly mounted with said upper piston to form the inner vertical wall and at least a portion of the top wall of the rim housing of the cap, and a central diaphragm plunger slidably mounted in said head and spring pressed downwardly to engage the cap blank and be retracted into said head prior to the cupping operation.

11. A die as set forth in claim 8 in which the upper piston carries packing to form a pressure seal with said upper cylinder and said upper diaphragm forming member is provided with a head slidable in said upper cylinder and engaging the lower end of said upper piston to be actuated therewith, said head also having packing means forming a pressure seal with said upper cylinder.

12. A die as set forth in claim 1 in which the lower draw ring comprises an outer sleeve and a head slidable therein, said head conforming to the inner and top walls of the cap rim housing and being spring pressed upwardly to strip the cap skirt from said sleeve.
